Charles B. Hobbs, Decatur, Ill., assignor to U. S.
Manufacturing Corporation, Decatur, Ill., a corporation of Illinois

Application May 5, 1948, Serial No. 146,172

Term of patent 14 years

(Cl. D44—1)

To all whom it may concern:

Be it known that I, Charles B. Hobbs, a citizen of the United States of America, residing at Decatur, in the county of Macon and State of Illinois, have invented a new, original, and ornamental Design for a Broiler, of which the following is a specification, reference being had to the accompanying drawings, forming a part thereof.

Fig. 1 is a perspective view of a broiler showing my new design;

Fig. 2 is an end view;

Fig. 3 is a top view on a reduced scale; and

Fig. 4 is a side view also on a reduced scale.

I claim:

The ornamental design for a broiler, as shown.
CHARLES B. HOBBS.
